UNITED STATES PATENT OFFICE.

JOSEPH ASTESANO, OF ROANOKE, ILLINOIS.

VEGETABLE CUTTER.

Application filed June 18, 1923. Serial No. 646,148.

To all whom it may concern:

Be it known that I, JOSEPH ASTESANO, a citizen of the United States, residing at Roanoke, in the county of Woodford and 5 State of Illinois, have invented new and useful Improvements in Vegetable Cutters, of which the following is a specification.

This invention relates to culinary implements, and more particularly to devices intended for cutting or grating vegetables.

An object of the invention is to provide a vegetable cutter which is readily adaptable to the cutting or grating of various kinds of vegetables, and in which the cutting instrumentality is quickly removable for the substitution of cutting members of different constructions.

Other objects of the invention are to provide a device of simple and relatively inexpensive construction; to provide means for automatically feeding the vegetable or other article to be cut to the cutting drum, whereby the operator, after once placing the vegetable within the device need merely give 25 his attention to the operation of the cutting drum; to provide for the ready removal of the cutting drum, and to insure a rigid and durable construction which will always be positive in operation and will require a minimum of care and attention for its maintenance in proper working order.

In the drawings, wherein there is disclosed an embodiment of the invention—

Fig. 1 is a vertical section,

Fig. 2 is a section on the line 2—2 of Fig. 1 looking in the direction of the arrows, and

Fig. 3 is a fragmentary elevational view of a modified form of cutting drum.

Referring to the drawings for a more detailed description, 10 indicates a base or support carrying a pair of standards 11, 12, which support, between them, a housing 13 having an open top through which the material may be introduced into the housing and an outlet or discharge opening 14 in its bottom. The standard 11 has a bearing 15 at its upper end for a stub shaft 16 extending through the wall of the housing, and a 45 boss 17 upon the interior of the housing, which serves as a bearing for the shaft. The standard 12 has a hollow boss 18 through which passes a stub shaft 19 normally urged, by means of a spring 20 engaging a collar 21 on the shaft, into the housing and through a boss 22 upon the housing, the

latter serving as a bearing for the shaft in conjunction with the boss 18 upon the end of the standard. The shafts 16 and 17 are adapted to carry a cutting instrument, such as a drum 23, the latter being placed in the housing through its top, and the shaft 19 being retracted by means of a hand grip or head 19' to permit the end of the shaft to be inserted in an axial opening 24 in a head 25 of the drum. The shaft 16 has a squared head 16' which projects into an opening in the opposite head 26, the heads having peripheral rims 27 carrying a metallic cutting sheet 28, in which fin portions 29 are struck up to effect the cutting. It will be noted that the drum is removably supported within the housing by means of the two shafts, 16, 19, and may be readily moved by retracting the shaft 19 to permit the insertion of a different type of cutting drum. In Fig. 3 there is shown a portion of a drum having relatively small cutting projections 30 formed thereon, each projection being of substantially frusto-conical shape, as distinguished from the substantially parallel fins or ribs 29 of the drum shown in position within the housing in Figs. 1 and 2.

The drum is operated by means of a hand crank 31 upon a shaft 32 mounted in a boss 33 on the standard 11, the shaft carrying a spur gear 34 meshing with a spur gear 35 fixedly mounted on the end of the shaft 16.

For the purpose of insuring a continuous feed of the material to be cut or grated to the drum, the housing has a cover 36 which may be secured in position by means of spring fingers 37 engaging a rim 37' on the housing. The cover has in association therewith, within the housing, a follower plate 38, which is normally pressed, by means of springs 39, downwardly in the direction of the drum to engage a vegetable which is positioned between the follower and the drum. The follower maintains a yielding pressure upon the vegetable and as the bulk of the latter is decreased during the operation of the drum the vegetable is fed evenly and continuously toward the drum under the pressure of the follower plate. In order to limit the downward movement of the plate and to prevent engagement of the latter with the drum, stops 40 are provided upon the interior of the housing, the edges of the follower engaging these stops when the follower reaches the limit of its downward movement, as

shown in Fig. 2. The cover 36 also carries depending strips 42 having terminal lugs 43 which serve to limit the movement of the follower plate under the influence of the springs. Lugs 43, when the cover is in position, are located below the stops 40 so that they do not interfere with the operation of the follower plate, and merely function when the cover is removed, together with the follower plate.

In operation, the vegetable to be cut or sliced is placed within the housing and the cover is then positioned upon the top of the housing with the follower plate engaging the vegetable. The drum is then operated by means of the crank 31, which results in the cutting of the vegetable and the discharge of the portions thereof through the opening 14. It will be noted that this opening is positioned in the bottom of the housing and the cutting portions naturally gravitate to the opening due to the inclination of the bottom wall 14' toward the opening. Additionally, the centrifugal action of the drum tends to throw the portions downwardly, and these two forces insure the quick removal of the cut vegetable so that the normal action of the cutting instruments is not impeded.

It should be understood that numerous modifications may be made in the illustrated

and described structure without departing from the scope of the invention, which is more precisely defined in the following claim.

I claim:

A vegetable cutter comprising a pair of standards, a housing between and carried by said standards, a shaft on one of said standards projecting into the housing, a driving shaft projecting into the housing and having a bearing in the other standard, the two shafts being adapted to engage and support a drum within said housing, a drum removably carried by said shafts, yielding means for pressing one of said shafts into engagement with said drum, the shaft being longitudinally movable, said housing having an inlet opening above the drum and a discharge opening in its bottom below the drum, a cover for said inlet opening, a guide carried by said cover and depending into the housing, a spring pressed follower associated with said guide, means on said guide for limiting the movement of the follower away from said cover, the follower and guide being removable with the cover from the housing.

In testimony whereof I have hereunto set my hand.

JOSEPH ASTESANO.
